UNITED STATES PATENT OFFICE

CHRISTIAN GOTTWALD, OF CLEVELAND, OHIO, ASSIGNOR TO THE RIC-WIL COMPANY,
OF CLEVELAND, OHIO, A CORPORATION OF OHIO

IMPROVED THERMO PACKING MATERIAL

No Drawing.

Application filed March 17, 1928. Serial No. 262,592.

This invention relates to heat insulating compositions which are used wherever it is desired to enclose or pack pipes, or in other instances where thermo-nonconductivity is desirable.

The present heat insulating composition has particularly the property of being water repellent, so that the packing will not become water soaked and thus break down its qualities as a thermo-nonconductor, but rather will shed the water and prevent its penetration into the interstices of the materials making up the composition.

The present heat insulating composition is particularly useful in under-ground conduit systems in which steam pipes or similar pipes are located, and in which moisture frequently accumulates, due to condensation of escaping steam or from the ingress of water from the outside. When under such conditions the heat insulating material becomes water-soaked its thermo-nonconductivity is practically entirely broken down, so that it becomes useless for the purpose for which it was intended.

The usual forms of thermo-nonconductors, such as asbestos, rock wool and mineral wool which are in their nature composed of silicious fibers, are of themselves water-proof, that is to say the fibers themselves will not absorb water, but when such fibrous material is used for thermo packing material, it is necessary that the mass be not unduly compacted but rather be in a more or less loose state in order to provide the necessary heat insulating properties.

It is this very fact that provides interstices between the fibers and the particles of which the packing is composed and the water, either condensation water or water coming in from the outside, fills the interstices between the fibers or particles of this silicious and naturally water-proof material and is retained in these interstices, thereby causing the packing material as a whole to become water-logged, and hence not only nonefficient but practically useless for its intended purpose.

The present invention relates to a packing material which is composed of silicious fibrous material together with comminuted

sponge, in which the combined materials are treated to make them water-repellent. Additionally the invention comprises a packing material composed of silicious fibrous material intimately mixed with comminuted sponge where the sponge material has been treated not only for the purpose of removing its impurities but to expand it and increase its bulk or volume per unit of weight over that which the sponge naturally has after being gathered from the sea and dried.

Sponge material, as is well known, is a vegetable product growing beneath sea water, and when gathered and dried retains in its pores certain of the salts which are dissolved in the ocean water. If this sponge material be fixed with fibrous packing material, such as asbestos, and used as a heat insulating packing material enclosing metal pipes, particularly iron pipes, and the water either from condensation within the conduit or by water finding its way into the conduit, comes in contact with the packing material, the salts in the sponge in rather concentrated form are dissolved by the water and frequently attack the pipe setting up a chemical action which may continue for a period of time and cause serious damage to the pipes.

Furthermore, the untreated or natural dried sponge is not so porous and bulky as is the treated sponge and, therefore, the treated sponge is a much more efficient and desirable material to combine with the asbestos or other silicious fibrous material for the purpose of making a packing material.

In making up the packing material the sponge is comminuted in any suitable manner so that the particles are practically the size of a pea or bean. The sponge is thoroughly treated to remove the salt, the process including a thorough washing and subsequent drying. This results in the sponge becoming more bulky and consequently more porous.

The prepared sponge is mixed with shredded asbestos or other fibrous mineral material, this mixture being effected in any desirable manner so as to thoroughly and intimately mix the sponge and the silicious fibrous material. Experience has demonstrated that by proper mixing, the fibrous or silicious ma-

terial will wrap around the sponge particles until upon superficial view it is impossible to detect the presence of the sponge. This mixture of the asbestos and sponge produces a fluffy unmatted mass which is particularly suitable for use as a heat insulating material, because of its bulkiness and its fluffy quality.

Perhaps the most important characteristic which the sponge imparts to the mixture is that of preventing the sagging of the material after it has been in use for a period of time. When the packing material is placed in position in a conduit and surrounding a pipe it is necessary that there be a certain looseness in the packing material in order to provide efficient heat non-conductivity.

There is a tendency for the packing material to settle after it has been in position for a time, but where the comminuted sponge is mixed with the asbestos the packing material does not sag to any appreciable extent.

The mixture which has just been described may be used as a heat insulating packing under many circumstances even without the mass being treated to render the same water repellent. However, I prefer to treat the mixture of sponge and asbestos in order to render the material water repellent. This may be done in a variety of ways, one of the ways being to treat the mixture of sponge and asbestos with dry pulverized metallic soap, such as aluminum stearate. If a thorough mixture of the sponge and silicious material together with a suitable quantity of aluminum stearate be effected, the fibers of the asbestos and the spongy material are thoroughly coated, in the case of asbestos fibers, and the spongy material is thoroughly impregnated with the aluminum stearate, with the result that the packing material is rendered water repellent.

By water repellent is meant something different from water proof. Silicious fibers, such as asbestos fibers, are in and of themselves water proof for they are of mineral matter. However, as I have before pointed out in this specification, a mass of fibrous mineral material, such as asbestos, although it is naturally waterproof, may nevertheless become impregnated with water and thus become water soaked, so as to entirely destroy its heat insulating properties.

Treating the fibers of the asbestos to make them water repellent and also treating the spongy material to make it water repellent results in producing a packing material which has the desired characteristics as to bulkiness and fluffiness, at the same time possessing the additional desired characteristic that it is water repellent, so that if this packing material be used in a conduit and surrounding pipes through which steam or other fluid is passing and water finds its way into the conduit, either from the outside or by condensation of mixture on the inside, the

water does not find its way into the interstices of the packing material, but rather is repelled and drains into the bottom of the conduit where, as is customary, suitable provision is made for its drainage.

While the invention herein disclosed has been more particularly in connection with the use of the packing material for underground conduit use, it will be understood that this material may be used in other ways where a moisture proof or water repellent material may be desirable, such for instance in packings for refrigerators, fire-proof cabinets or other like structures.

Having thus described my invention what I claim as new is,

1. A heat insulating composition comprising a fluffy, unmatted mass consisting of an intimate mixture of shredded fibrous mineral material, and comminuted sponge which has been treated with a metallic soap to render the same water repellent.

2. A heat insulating composition comprising a fluffy, unmatted mass consisting of an intimate mixture of shredded fibrous mineral material, and comminuted sponge which has been treated with a dry metallic soap to render the same water repellent.

3. A heat insulating composition comprising a fluffy, unmatted mass consisting of an intimate mixture of shredded fibrous mineral material, and comminuted sponge which has been treated with aluminum stearate to render the same water repellent.

In testimony whereof, I hereunto affix my signature.

CHRISTIAN GOTTWALD.
